UNITED STATES PATENT OFFICE.

WILLIAM G. WORRELL, OF WAXAHACHIE, TEXAS.

TOLLING APPARATUS.

1,412,441.

Specification of Letters Patent. Patented Apr. 11, 1922.

Application filed October 25, 1920. Serial No. 419,267.

To all whom it may concern:

Be it known that I, WILLIAM G. WORRELL, a citizen of the United States, residing at Waxahachie, in the county of Ellis and State of Texas, have invented certain new and useful Improvements in Tolling Apparatuses, of which the following is a specification.

This invention relates to new and useful improvements in tolling apparatuses.

It is customary for the miller to receive, as toll, a portion of the grain ground for the customer. This invention has to do with means for automatically taking the miller's toll and also the segregation of different kinds or qualities of grain.

The object of the invention is to utilize the flow of the grain to operate means to set the apparatus in motion and also to manipulate by the flow of the grain, means for causing the discharge of the grain into a segregated bin for the reception of the grain, whereby each kind or quality of grain selects its own bin.

A further object is to divide the grain so that the toll is carried to the miller's bin and the customer's portion is carried to the grinding mill. Another object is to employ the flow of the grain to stop the operation of the apparatus.

An apparatus designed to carry out the invention will be hereinafter described together with other features of the invention.

The invention will be more readily understood from a reading of the following specification and by reference to the accompanying drawings, in which an example of the invention is shown, and wherein:

Fig. 1 is a side elevation of an apparatus embodying the invention, portions being illustrated in section to show interior parts.

Fig. 2 is a detail of the grain bin valve mechanism.

Fig. 3 is a side elevation of the hoppers and component parts.

Fig. 4 is a side elevation of the grinding mill, and

Fig. 5 is a plan view of the elevator driving means.

In the drawings the numeral 10 designates a base on which is an upright frame comprising, studs 11 having a cross beam 12 at their tops. A pair of feed hoppers 13 and 14 respectively, are suitably mounted on hangers 15 and 15' secured on the beam 12. The hopper 13 has a depending spout 13',

while the hopper 14 has a similar spout 14'. The spouts are inclined forwardly from the hoppers and are mounted on braces 16 fastened to the studs. The lower ends of the spouts are positioned over a receiving hopper 17 held between the studs by braces 18. The hopper 17 is mounted at the upper end of a vertical chute 19.

The chute has its lower end discharging into the boots 20 and 21 respectively of a toll elevator 23 and mill elevator 24 diverging from each other. The boots are separated by an upstanding deflector partition 22 located so as to deflect the falling grain into the boots. It will be seen that if the deflector is located centrally of the chute, the grain will be evenly divided between the two boots and consequently the location of the deflector controls the division of the grain.

In the toll elevator 23 an endless bucket conveyer 20' is disposed and a similar conveyer 21' is arranged in the mill elevator 24. The conveyers have their lower ends passing around pulleys 25. The upper end of the conveyer 21' passes around a pulley 26 mounted on a shaft 27; while the upper end of the conveyer 23 passes around a pulley 26' mounted on a shaft 27'. The shafts are driven by means hereinafter described, so as to propel the conveyers to elevate the grain.

A discharge spout 28 depends from the head of the elevator 23 into the upper ends of a pair of toll bins 30 and 31 respectively. The upper end of a partition 30' projects up into the lower end of the spout, centrally thereof, and separates the bins. A valve 29 is hinged along the upper edge of the partition and is adapted to have its upper edge rest against either side wall of the spout, so as to obstruct the passage of the grain to one bin and deflect it into the other bin. The valve has a horizontal shaft 29' extending rearwardly from the spout and provided with a bevel gear 32 on its end, which meshes with a bevel gear 33 mounted on a shifting shaft 34 carried by the studs, see Figs. 2 and 3.

In the spouts 13' and 14' gates 35 extend from shafts 36 so as to project transversely of the spout and when swung downward, to rock said shafts 36. The shafts extend through the sides of the spouts and each has a depending lever 37 fixed on its outer end. A connection 38 extends from the lower end

of each lever. A pair of diametrically opposite arms 39 are provided on the shaft 34. The upper end of one of these arms receives the end of the connection 38 from the spout 14'; while the lower end of the other arm is attached to the connection 39 of the spout 13'. The gates are arranged so that when one is obstructing the passage of grain through its spout, the other is swung down and will be swung upward, when the first named gate is depressed.

It will be seen that the depression of the gate in the spout 13' will rock the shaft 34 in an opposite direction to the direction in which it is rocked by the depression of the gate in the spout 14'. Consequently when the gate in the spout 13' is depressed by the grain, the shaft 34 is rocked so as to rotate the shaft 29' and swing the valve 29 to the left (Fig. 1), thus deflecting the grain into the bin 31. When the gate in the spout 14' is depressed the shafts 34 and 29' are rocked in the opposite direction and the valve 29 swung to the right (Fig. 1) so as to deflect the grain into the bin 30.

A spout 40 depends from the upper end of the elevator 24 into a hopper 41 mounted on the upper end of a vertical chute 42 mounted in a grinding mill 43, which latter may be of any suitable construction. An electric motor 44 is mounted adjacent the mill and has a pulley 45 on its armature shaft which drives a belt 46. The belt drives a pulley 47 mounted on the shaft 48 of the mill. The shaft 48 extends through the mill and has a sprocket wheel 50 fastened on its opposite end. The wheel 50 drives a sprocket wheel 52 by means of a sprocket chain 51. The sprocket wheel 52 is fastened on the shaft 27. The parts are operated so as to operate the conveyer 21' to elevate the grain from its boot 21, as is indicated by the arrows.

For driving the shaft 27' of the conveyer 20' in reverse direction to the shaft 27, a bevel gear 53 is fastened on the shaft 27. A shaft 55 is supported in boxes on the studs. A bevel gear 54 mounted on the right hand end of this shaft is driven by the gear 53. A bevel gear 56 mounted on the left hand end of the shaft meshes with a bevel gear 57 mounted on the shaft 27', so as to revolve the latter in a reverse direction to the shaft 27.

One of the features of the invention is to utilize the flow of the grain to start and stop the motor 44. The electrical circuit to the motor comprises a wire A forming one side of the circuit and a wire B leading from the motor and constituting the other side of said circuit. The wire B leads to a rheostat 60 from which a wire C leads to complete the circuit. A wire B' branches from the wire B to a second rheostat 61 from which a branch wire C' leads to the wire C. The rheostat 60 is located on the chute 19 and its arm 60' is swung by a flap 62 hinged in the

chute and normally extending horizontally across the same, in which position the arm 60' is at the lower end of its segment and the circuit is open. When the flap is depressed by the grain flowing down the chute 19, the arm is swung and the circuit to the motor is closed.

The rheostat 61 is located on the chute 42 and has its arm 61' connected with a flap 63' in the chute. The reason for the second rheostat is to keep the circuit closed and the mill running after the grain ceases flowing through the chute 19 and until it ceases to flow down the chute 42. Each arm 60' and 61' has a lever 63 attached to one end of a coiled spring 64 having its opposite end suitably supported. When a flap is depressed the lever is swung by its arm and the spring extended; thus when the grain ceases to flow past the flap, the spring returns the parts to their normal position.

The apparatus is operated as follows:

The customer selects the feed hopper which is marked to receive the particular quality, color or kind of grain he has to be ground. For instance the hopper 13 may be for white corn and the hopper 14 for yellow corn. We suppose the customer has white corn so he dumps the same into the hopper 13. The grain passes down the spout 13' and depresses the gate 35, whereby the lever 37 attached thereto is swung and the shaft 34 rocked, by its arm 39 which is swung rearward, thus swinging the valve 29 to the left (Fig. 1) and closing the bin 30.

The grain passes down the spout 13', into the hopper 17 and down through the chute 19. As the grain passes down the chute 19 the flap 62 is depressed and the arm 60' of the rheostat 61 is swung upward. This closes the circuit to the motor over the wires A, B and C and starts the motor. The motor drives the mill 47 and revolves the shaft 48 by the belt 46. The shaft 48 drives the chain 51 which revolves the shaft 27 and also the shaft 27' by the countershaft 55 and its gears. The shafts 27 and 27' being driven in opposite directions cause both conveyers 20' and 21' to travel upwardly.

The grain is discharged from the bottom of the chute 19 and the flow is divided by the partition 22, a portion being deflected into the boot 20 as toll, and the remainder into the boot 21 to be conveyed to the mill 43. The grain received in the boot 20 is elevated by the conveyer 20' and discharged into the spout 28 from which it is discharged into the bin 31.

The grain received is in the boot 21 elevated by the conveyer 21' and discharged from the spout 40 into the hopper 41, from which it passes down through the chute 42. As the grain flows through the chute 42 it depresses the flap 62; thus operating the rheostat 61 to close the circuit to the motor over the wires 125

A, B, B', C' and C. After the grain ceases to flow past the flap 62, the spring of the arm 60' returns the arm, swings the flap up and opens the circuit at this point. The 5 motor continues to operate until the grain ceases flowing over the flap 62', at which time the circuit is opened and the apparatus stopped as will be obvious.

It is pointed out that no attendant or operator is required with this apparatus. The 10 operation is automatic after the customer selects the proper feed hopper.

What I claim, is:

1. In a tolling apparatus, a plurality of 15 feed hoppers, a separate toll bin for each hopper, means for dividing a fluent commodity flowing from one of the hoppers into a toll portion and a customer's portion, means for conveying the toll portion of the commodity to the toll bins, and means having connection with each hopper and operated by the flow of the commodity therethrough for directing the toll portion of the commodity into the toll bin correlated with the 25 hopper through which the commodity flows.

2. In a tolling apparatus, the combination of a pair of conveyers, means for receiving a flowing commodity arranged to divide said commodity into a toll portion and a customer's portion, one of which portions is delivered to one conveyer and the other of which is delivered to the other conveyer, a pair of toll receptacles receiving the commodity from the conveyer to which the toll 30 portion of the commodity is delivered and means for diverting the toll commodity into either of the receptacles.

3. In a tolling apparatus, a pair of conveyers, means for receiving a flowing commodity arranged to divide said commodity into a toll portion and a customer's portion, one of which portions is delivered to one conveyer and the other portion to the other conveyer, toll receptacles receiving the toll 40 commodity from the toll conveyer, and means operated by the flow of the commodity prior to its division into two portions for selecting the particular toll receptacle into which the toll portion of the commodity 45 is to be discharged.

4. In a tolling apparatus, a tolling conveyer, a second conveyer, means adjacent the conveyers for receiving a flowing commodity and dividing it into two portions, one of 55 which portions is delivered to the tolling conveyer and the remainder of which is delivered to the second conveyer, means for operating the conveyers, and means for controlling the operating means located in advance 60 of the point of division of the commodity and set to operate by the flow of the commodity.

5. In a tolling apparatus, a tolling con-

veyer, a second conveyer, means adjacent the conveyers for receiving a flowing commodity and dividing it into two portions, one of which portions is delivered to the tolling conveyer and the remainder of which is delivered to the second conveyer, means for operating the conveyers, means for controlling the operating means located in advance of the point of division of the commodity and set to operate by the flow of the commodity, and a second controlling means for the operating means located to be operated by 70 the commodity flowing from the second conveyer.

6. In a tolling apparatus, a plurality of feed hoppers, a toll bin for each hopper, a valve controlling the entrance of a commodity into the bins, means operated by the flow of the commodity through the feed hoppers for operating the valve to divert the commodity into the particular bin correlated with the hopper through which the 80 grain flows, a tolling conveyer for conveying the commodity to the bins, a second conveyer, and means for dividing the commodity so that a portion will flow to the tolling conveyer and the remainder to the second 85 conveyer.

7. In a tolling apparatus, a pair of feed hoppers having depending spouts, a receiving hopper below the spouts, a tolling elevator, a mill elevator diverging from the tolling elevator, a dividing element between the elevators for dividing a commodity flowing from the receiving hopper between the elevators, a pair of toll bins into which the tolling elevator discharges, a valve arranged to 90 deflect the discharge into either of the bins, gates in the spouts of the feeding hoppers, and means operated by the gates and connected with the valve for positioning the latter to deflect the commodity into the bin 95 correlated with the particular gate operated.

8. In a tolling apparatus, a pair of feed hoppers having depending spouts, a receiving hopper below the spouts, a tolling elevator, a mill elevator diverging from the tolling elevator, a dividing element between the elevators for dividing a commodity flowing from the receiving hopper between the elevators, a pair of toll bins into which the tolling elevator discharges, a valve arranged to 100 deflect the discharge into either of the bins, gates in the spouts of the feeding hoppers, means operated by the gates and connected with the valve for positioning the latter to deflect the commodity into the bin 105 correlated with the particular gate operated, and means for driving the elevators automatically set to operate by the flow of the commodity.

In testimony whereof I affix my signature. 115
WILLIAM G. WORRELL.
